UNITED STATES PATENT OFFICE.

WILLIAM J. PFEIFER, OF OAK PARK, ILLINOIS.

DAMPER MECHANISM OR DRAFT REGULATOR.

Application filed October 20, 1924. Serial No. 744,658.

To all whom it may concern:

Be it known that I, WILLIAM J. PFEIFER, a citizen of the United States, residing in Oak Park, in the county of Cook and State 5 of Illinois, have invented certain new and useful Improvements in Damper Mechanisms or Draft Regulators, of which the following is a specification.

This invention relates to damper mechanisms, or draft regulators, comprising a damper member adapted to be automatically operated or actuated, for controlling or regulating the draft of a furnace or heater, or similar device.

15 The principal object of the invention is to provide an improved, simple, economical, and efficient damper mechanism, or draft regulating or controlling mechanism for furnaces, heaters, or similar devices.

20 A further object of the invention is to provide an improved damper mechanism or draft regulator comprising a damper member adapted to be actuated or operated automatically by the action or force of a current of air or gases, or air and products of combustion passing into or through the flue or from the combustion chamber or fire box of a furnace, or similar device.

A further object of the invention is to 30 provide an improved damper mechanism or draft regulator adapted to be automatically actuated independently of the temperature or pressure of the water or steam in the boiler or heating chamber of a furnace, so as to automatically control or regulate the draft and prevent the escape of smoke from the firebox through the furnace door when such door is opened to build or replenish the fire.

40 Other and further objects of the invention will appear from an examination of the following description and claims, and from an inspection of the accompanying drawings, which are made a part hereof.

45 In the accompanying drawings:—

Figure 1 is a view in side elevation of a furnace provided with damper mechanism constructed and adapted to operate in accordance with my invention;

50 Fig. 2 is a view in front elevation of the furnace shown in Fig. 1, with the upper part of the furnace broken away or omitted, and showing the means for connecting the damper-operating mechanism with the firebox door;

Fig. 3 is an enlarged view in side elevation of a flue provided with a smoke box or chamber and damper mechanism constructed in accordance with my invention, and showing the damper-operating mechanism in initial position in full lines, with the dampers in corresponding or open position, the dampers being shown in closed or released position and the damper-operating mechanism in a corresponding position in broken lines;

Fig. 4 is a view in side elevation of a furnace provided with damper mechanism constructed in accordance with my invention, showing my improved dampers and damper-operating mechanism adapted to be attached to or used in connection with a furnace or heater having an upright opening or flue leading into or through the bottom of a smoke box or damper-containing chamber in accordance with my invention;

Fig. 5 is an enlarged view in side elevation, similar to Fig. 3, of a smoke-box or damper-containing chamber provided with dampers and damper-operating mechanism constructed in accordance with my invention and adapted to be attached to an upright opening or flue of a furnace or heater as shown in Fig. 4, and showing a modified form of connecting means for connecting the damper-mechanism with the furnace door; and

Fig. 6 is an enlarged detail view of my improved damper and damper-operating and releasing mechanism.

In constructing an improved damper mechanism or draft regulator for furnaces or heaters, or similar devices, in accordance with my invention, I provide a furnace or heater 1, which may be of any desired, ordinary and well-known or suitable form. The furnace or heater is provided with the usual combustion chamber or firebox 2, grate 3, firebox door 4, ash-box 5, boiler or heating chamber 6, flue 7, smoke-box or chamber 8, 100 and inclosing walls or furnace walls 9, all of which may be of the usual, or any desired, ordinary and well-known or suitable form.

The furnace or heater 1 may be either of the upright or vertical form, or of the horizontal type, both of which are well-known and in common use, or of any desired, ordinary and well-known, or suitable form.

The furnace or heater is also, by preference, provided with one or more ash doors 110

or front dampers or doors 10, 10' or other suitable means for admitting or regulating the admission of air to the combustion chamber or firebox, through or from beneath the grate, or from the front of the firebox, or otherwise, as desired.

A damper 11 pivotally supported on a transverse rock-shaft or axle 12 is mounted in or in position to open and close or regulate, or control the effectual area of the passage 13 in the flue 7, or leading from the combustion chamber 2 to or through the flue, or through the smoke-box and flue. This damper 11 is, by preference, located at the intersection of the smoke-chamber 19 and flue 7, or in position to open and close or vary the effectual area of the passage or opening 13 between the smoke-box and flue or in the flue. I prefer to mount the damper 11 and a damper 22, which is operatively connected therewith, in a damper-containing chamber 19 between the smoke box 8 and flue 7.

The rock-shaft or axle 12 on which the damper is mounted and, by preference, fixed, so as to rock with the rock-shaft, is provided with a lever arm 14 on which is adjustably mounted a counter-weight 15 adapted to properly balance the damper 11. The damper and lever arm, both of which are, by preference fixed to the rock shaft 12, are thus so balanced that said damper will be normally in open or initial position when a relatively light or normal current of air or air and gases is passing through the flue 7 or damper-controlled passage 13, or, in other words, when the fire is normal or not so hot but that the damper may safely be left open. But the damper 11 in its open or initial position is so nearly balanced by its own weight and the properly adjusted counter-weight on the lever arm 14, that the damper will be released and operated to or in the direction of its closed position by the action of the current of air or gases or products of combustion passing through the damper-controlled passage or opening 13 and flue 7 or from the interior of the furnace whenever such current becomes excessive or above normal in volume or in its speed of movement, or whenever the furnace is in danger of becoming overheated and the fire becomes hotter and the draft stronger or more rapid than is desired or consistent with safety, or whenever it is desirable that the damper should be thus automatically closed either partially or wholly in order to insure safety or for any reason, for example, when the front fire door or damper has been left open, or the operator has inadvertently left any of the dampers or doors or the fire in a condition or position which would permit the fire to become too hot for safety or to exceed a desired predetermined temperature consistent with safety or comfort, and

the automatic closing of the damper by the action of the current or excessive draft of air or products of combustion through the damper-controlled passage or flue is desirable or necessary.

In order to provide means for automatically opening the damper 11 when the firebox door 4 is opened, or by the opening of said door, and adapted to leave the damper 11 in open position and in position to be automatically actuated by the draft or current of air passing from the firebox or combustion chamber into or through the flue, or through the smoke-box and flue, as already suggested, the damper 11 is operatively connected with said firebox door 4 by suitable connecting means. For example, a damper-operating bar or arm 18 is operatively connected with the damper 11 by means of a crank arm 17 fixed to the rock shaft 12, and having a crank pin 20 on said crank arm and extending into an elongated slot 21 in said damper-operating rod or arm 18. The elongated slot 21 is thus adapted to provide sufficient play or lost motion between the preferably reciprocating damper-operating bar or arm 18 and the damper 11, or between said arm 18 and the crank 17 and crank pin 20. The damper-operating rod or arm 18 is thus adapted to operate the damper in one direction or toward its opened position, as said arm or rod 18 is automatically operated in a corresponding direction by the opening of the door 4. But the door 4 is permitted to be closed, and the operator may operate the bar or arm 18 in an opposite direction without actuating or changing the position of said damper 11.

The damper-operating rod or arm 18 is, by preference, reciprocatingly mounted upon a suitable support, and also, by preference, operatively connected with a second or main damper 22, which is rockingly mounted upon a transverse axle 23 in position to open and close, or control, a passage 24, leading from the combustion chamber into the chamber 19, or to or toward the passage 13 and flue 7.

In order to enable this to be accomplished in a simple and efficient manner, and to enable the damper 22, as well as the damper 11, to be automatically operated in an efficient manner by the opening of the door 4, and to enable the damper 22 to be movable toward its closed position upon the closing of the door 4, and either without or with and by means of the operation of the damper 11, the arm or bar 18 is, by preference, operatively connected with the damper 22 and door 4, as well as with the damper 11, as follows:

A lever arm 25 is fixed to the axle 23 of the damper 22 and pivotally connected with the end of the arm or bar 18 by a pivot pin 26 on the end of said lever 25. The lever

25 and arm 18 are connected with the door 4 by suitable connecting means, such, for example, as the lever and chain mechanism shown in Fig. 1, which is constructed, by 5 preference, as follows:

A rocking lever 27 is mounted upon a suitable support 28 by means of a supporting hinge or pivot 29. The support 28 may be suspended from the ceiling or from any 10 desired stationary support. One end of the lever 27 is connected with the lever arm 25 and bar 18 by means of a chain or similar flexible element 30, one end of which is connected with the lever arm 27, and the other 15 end with the arm 25 or bar 18 by an eye 26'. The opposite arm 31 of the lever 27 is connected with a lever arm 32 of a bell-crank lever 33 pivotally mounted upon a pin or fulcrum 34 on a stationary support 20 35 adjacent to the door 4. The connection of the arm 31 with the lever arm 32 is by means of a chain 36, or similar flexible element, one end of which is connected with the arm 31, and the other with the arm 32. The arm 33 of the bell-crank lever is 25 40 operatively connected with the door 4 by suitable connecting means, such, for example, as a chain or flexible element 37, one end of which is attached to the door 4 by suitable securing means on the door, and 45 the opposite end with the lever arm 33.

The damper-operating arm or bar 18—being operatively connected with the rock shaft 12 and damper 11 fixed to said shaft, 50 by means of the elongated slot 20 in said bar 18 and the crank pin 20 on the crank or lever arm 17 and extending into said elongated slot, said lever arm 17 being fixed to said rock shaft 12 as already described—40 is also operatively connected with the second or main damper 22 by means of the lever arm 25, and a connecting pin 23 adjustably mounted in said lever arm 25 which is provided with a series of holes for receiving 45 said pin which is also adapted to be inserted in any desired one of a series of holes or notches 39 in a perforated or notched portion of said bar 18, or in any desired notch 40 of a series of such angular notches in a 55 notched connecting member or strip 41 pivotally connected with said bar 18 and adapted to be adjustably connected with the lever arm 25 and to form an adjustable connecting means between said lever 25 and said bar 18. The bar 18 thus connects the 60 dampers 11 and 22 in such a manner that the automatic closing of the damper 11 by the action of the current or draft of air and gases through the damper controlled passage 13 and flue 7, when such current becomes excessive, will cause the damper 22 to be automatically closed in case said damper 22 has been left open either intentionally or inadvertently. And the draft or current 65 of air and gases will thus be controlled, re-

duced or regulated by the automatic closing of both of said dampers thus operatively connected and automatically released and actuated. It will also be readily seen that the opening of the damper 22 either by 70 opening the fire-box door 4 or otherwise, will also operate the connecting damper-operating bar 18 and cause the damper 11 to be opened simultaneously with the opening of the damper 22. 75

It should also be noted that the operator, by grasping the damper-operating bar 18 or the knob 42 on said bar and slightly raising or pressing upward and rearward or toward the damper 11 may operate or 80 close the damper 22 without changing the position of or actuating or operating the damper 11. And it is obvious that after the damper 22 has thus been closed in such a manner as to leave the damper 11 open, the operator—by closing the fire-box door, or by operating the bar 18 in an opposite direction or forward—can open the damper 22 without actuating or affecting or changing the position of the already open damper 90 95 11. But the opening of the damper 22 will in any case cause the damper 11 to be opened and set in position to be automatically released and actuated by the action of the current or draft of air and gases through the damper-controlled passage or flue whenever such current becomes excessively strong or rapid.

The damper-operating bar 18 and damper 11 are also, by preference, operatively connected by releasable trigger-like connecting means, as follows:

The end of the bar 18 which is adjacent to the damper 11 and its supporting rock-shaft or axle 12, is provided with a notch 43 and shoulder 44 adapted to engage an adjacent locking or connecting and releasing shoulder 45 on a flat or angular end portion 46 on or forming a part of the rock-shaft or axle 12. And the lever arm or crank arm 17, already described, is fixed to said angular or flat end portion of the rock-shaft 12 by means of screws 47, or other suitable securing means, and the crank pin or tripping and connecting pin 20 anchored in said lever arm 17 and extending into the elongated slot 21 in the bar 18, is normally located forward and above the level of the axis of the rock shaft 12 and damper 11 and in position to move rearward over said axis with and in fixed relation to the rock shaft 12 when said rock-shaft and damper are rocked or partially rotated in a direction in which the damper 11 moves to closed position, or rearward. (See Fig. 6.) It will thus be readily seen that the movement or operation of the damper 11 and its rock-shaft 12 and lever arm 17 from open position, in which said damper is shown in full lines in said Figure 6, to or toward the closed 110 115 120 125 130

position of said damper and parts as shown in broken lines in said Fig. 6, will cause the shoulder 44 and notch 43 of the bar 18 to be raised out of engagement with or released from the locking shoulder 45 on the rock-shaft 12. This trigger-like or releasable locking connection between the bar 18 and the rock shaft 12 being thus released by the automatic operation or movement of the damper 11 to or toward its closed position, said operation or movement of the damper 11 will automatically release and actuate or permit the movement of the damper 22 to or toward its closed position simultaneously with the movement of the damper 11 to or toward its closed position as indicated in said Fig. 6. The releasable trigger-like connection between the shouldered end of the bar 18 and engaged shoulder 45 on the rock shaft or axle 12 of the damper 11 acts to releasably hold the damper 22 in its raised or open position, or in a locked position from which it can be automatically released by the closing of the damper 11. And although the opening of the damper 22 by the opening of the fire-box door, or in the ordinary operation of said damper 22 will open the damper 11; and the closing of the damper 11 will automatically close the damper 22, the damper 22 may be adjusted to any desired partially opened or adjusted position with respect to the damper 11. From the foregoing description, it will be readily understood by those skilled in the art that the damper 22, which is, by preference located in the flue or passage formed by the flue and communicating with the combustion chamber of the furnace, is adapted to control the effectual area of such passage, or to open and close or restrict and limit or control the size or capacity of such passage. The damper 22 is, furthermore, provided with damper-operating means comprising the rockingly mounted damper 11, and its weighted lever arm 14, and connecting rod or bar 18, and the lever arm 25 fixed to the axle 23 and adjustably connected with the connecting rod or bar 18, so as to enable the damper 22 to be adjusted with respect to the damper or weighted rockingly-mounted damper-operating means or member 11. The weighted, damper-operating means, comprising said damper 11 and its counter-weight, and connecting rod and lever mechanism above described, is thus adapted to be actuated in one direction automatically, by the action of the current passing through the passage formed by the flue; and is adapted to be operated or actuated in an opposite direction by the closing of the combustion chamber door or fire-box door 4 of the furnace, or other suitable means for returning the damper 11 to its initial position. I prefer to have the damper 11 so constructed, mounted and counter-

weighted that it is adapted to be automatically moved to or towards its closed position by the action of the current, as already described, and as shown in the drawings, although it is possible to have said damper 11, when used in conjunction with another main or auxiliary damper, such, for example as the damper 22, so arranged and mounted and counterweighted that said damper 11 will be automatically moved by the current in the direction already shown and described or in the direction of the movement of the current, but to an open or partially open position of such damper 11 from a closed or relatively more nearly closed position. And I prefer to employ a plurality of dampers, such, for example, as the dampers 22 and 11, rather than a single damper 11.

In the form of the device shown in the drawings the weighted damper 11 is so constructed, mounted and counter-weighted that the center of gravity of the weighted damper 11 or rockingly mounted damper-operating means comprising said weighted damper 11 is normally on the front side of the horizontal axis of said damper, thus tending to releasably hold the weighted damper in its forward or initial position, as shown, for example, in full lines in Fig. 5. And upon being subjected to the action of a current of air or air and gases flowing through the passage 13 or flue 7 at or in excess of a desired speed of movement or predetermined speed or force of such current, said weighted damper will be automatically moved to or toward the position in which it is shown in broken lines in said Fig. 5, thus causing the center of gravity of the weighted damper to move in the direction of movement of the current and over or across the axis of the damper to the rear or opposite side of said axis, or to such a position that the weight and center of gravity of the damper will tend to hold the damper 11 in such last-mentioned position, as indicated in broken lines in said Fig. 5, and also in Fig. 3.

In Figs. 1 to 3 inclusive, my improved damper mechanism is shown in a form which is well adapted for attachment to and use in connection with a furnace or heater having a rear or approximately horizontal flue or outlet passage to be controlled by such damper mechanism.

In Figs. 4 and 5, however, a modification of my improved device is shown which is adapted for attachment to and use in connection with a furnace or heater having an upper or approximately upwardly directed passage in the upper part or top of the furnace or heater.

In the form of the device shown in said Figs. 4 and 5, the damper 22 is so connected with the damper 11, by means of the connecting rod 18 and lever arms 25 and 17, that the damper 22 is adapted to be moved

from its upper initial or open position as shown in full lines in Fig. 5, to its lower approximately horizontal closed or partially closed position across the flue opening or discharge opening 43 in the top of the furnace—which opening 43 corresponds with the bottom opening 44 in the bottom wall of the damper-containing chamber or smoke box 19 of my improved damper mechanism or draft regulator,—by the action of the current upon the damper-operating means or damper 11 shown in said Fig. 5, and already described. In order to enable this to be accomplished in a simple, economical and efficient manner, it is only necessary to connect the damper 22 with its axle 23 at a different angle with respect to the lever arm 25, or in substantially parallel relation to said lever arm, as shown in said Fig. 5, and to lower the damper to the position shown in said Fig. 5, or, in other words, to so mount the rocking damper 22 that its initial position will be approximately upright, and its closed position will be substantially horizontal and over and across the opening 23 in the top of the furnace and opening 24 in the bottom of the damper-containing chamber or smoke box 19.

In the form of the device shown in Figs. 4 and 5, the opening 45 shown in Fig. 3 is, of course closed. And in the form of the device shown in Figs. 1 and 3, the bottom opening 44 in the bottom of the damper-containing chamber or smoke box 19, as shown in Fig. 5, is of course closed and not used.

The differences in the positions of the openings controlled by the damper 22, and in the position of the damper 22 with respect to the opening controlled thereby, and with respect to the lever arm and connecting rod mechanism, or means for operating the damper 22 in the two forms of the device, one of which is shown in Figs. 1 and 3, and the other of which is shown in Figs. 4 and 5, are shown in said figures; and these differences necessitate certain modifications in the construction and arrangement of the stops for stopping or limiting the movements of the dampers 22 and 11, as shown in the drawings.

In the form of the device shown in Figs. 1 to 3 inclusive, an adjustable stop 46 is provided, having notches 47 therein. This adjustable notched stopping member 46 is adapted to extend through and is adjustable with respect to a loop or support 48. And a hinged or pivoted guiding arm 49 is pivotally connected at one end with the notched bar or adjustable stop member 46 by suitable means, such, for example, as a pin 50. And the other end of the arm 49 is connected with a stationary support, such, for example, as the wall of the smoke box or damper-containing chamber 19 by means of

a stationary supporting pivot pin 51, or other suitable securing means. The adjustable stop 46 is thus adapted to engage and stop or limit the movement of the lever arm 25 fixed to the damper 22, and thereby stop or limit the movement of the damper 22 in the direction of its closed or lowered position, and serves to stop said damper in any desired partially open or adjusted position. (See Fig. 3.)

In the form of the device shown in Figs. 4 and 5, the notched adjustable stop or bar 46 is inverted and inserted through the loop or support 48, which is secured in proper position as shown in Fig. 5. And the pivoted guiding arm 49, connected with said stop member 46 is also inverted with said notched stop member 46 and supported by the pin 51 or other suitable support, in position to guide said stop member 46. In all other substantial respects the devices shown in Figs. 1 to 3, and in Figs. 4 and 5, respectively, are substantially alike in construction and operation, differing only in details as shown.

The notched bar or adjustable stop member 46 is provided with end flanges 52, 53 at its opposite ends, one or the other of which is adapted to engage the lever arm 25 fixed to the damper 22 and limit the movement of said arm and damper downward or toward or to the lowered or closed position of the damper.

An adjustable stop 54, which is, by preference, slidably or adjustably mounted upon supporting pins 55 which extend into an elongated slot 56 in said stop, or upon a suitable support which may be of any desired ordinary and well known or suitable form, is adapted to engage and stop or limit the forward movement of the lever arm 17 fixed to the damper 11, and thereby limit the forward or forward and upward movement of the damper 11 from the position in which it is shown in broken lines in Figs. 3 and 5, respectively, to the position in which it is shown in full lines in said figures.

An adjustable transverse rocking bail-like stop 57 is also provided and mounted in the passage 13 or damper-containing chamber 8 adjacent to the damper 11 and in position to engage and limit the movement of the damper 11 in one direction, or from the forward initial position of said damper to or in the direction of its lowered position, which may be its closed, or partially closed, or open position, as desired.

This adjustable stop 57 is by preference in the form of a rod bent into the form of a bail and rockingly mounted adjacent to and across the downward or downward and rearward path of movement of the damper 11, said bail-like rod or stop having an outer integral lever arm portion 58 to the outer

- or swinging end of which is flexibly or pivotally attached a notched adjustable guiding and securing bar or hook 59. One end of the notched bar or hook 59 is provided with an aperture therethrough into and through which extends a horizontal angular outwardly projecting portion or connecting member 60 on or forming an integral part of the lever arm 58. (See Figs. 3 and 5.)
- 10 The adjustable guiding bar or hook 59 is provided with a plurality of notches 61 each adapted to be moved into and out of engagement with a stationary supporting or securing pin 62.
- 15 The transverse angular rocking bail or adjustable stop 57 is thus adapted to be adjusted to different positions with respect to the axis of the damper 11 and the opening 13 to be controlled by said damper, so as
- 20 to stop or limit the movement of the damper 11 as it is automatically actuated or released and operated by the action of a current of air or air and gases moving through the passage at or in excess of a desired or pre-
- 25 determined speed of movement of such current, or at or in excess of a predetermined speed of movement of such current which if allowed to continue or to increase would be dangerous, or liable to result in overheating
- 30 the flue or furnace, or unsafe or undesirable for any reason.

- From the foregoing it will be readily seen that the damper 11 is automatically actuated in the direction of the movement of the current by the action of the current moving in excess of a desired predetermined speed of movement consistent with safety, and by the action of gravity or the counter-weighted lever arm, and that the weighted or properly balanced damper 11 and its counter-weighted lever arm, and connecting rod 18 constitute an automatically actuated damper-operating means, for actuating the damper 22 as well as the damper 11.
- 45 In the device shown in Figs. 4 and 5, a modified form of connecting means for operatively connecting the damper mechanism or operating lever 25 and damper-operating and connecting bar 18 with the furnace door 4 and bell-crank lever 32 is shown, in which a chain or other suitable flexible element 30' is connected at one end with the lever 25 and bar 18 by means of an eye, such as the eye 26' already described, or by any ordinary and well known or suitable connecting means; and the chain or flexible element 30' extends through and is operatively supported by a pulley 54, suspended from or supported by the ceiling of the basement or room in which the furnace is located, or other suitable support. The opposite end of the chain or flexible element 30' is attached, by preference, to an arm of the bell-crank lever 32 already described, said lever being connected with the door

4 as already described. (See Figs. 1, 4 and 5.)

The damper 11, and its counter-weighted lever arm, and damper-operating mechanism, is capable of successful operation 70 by itself and without any other damper being connected therewith, such, for example, as the damper 22, but I prefer to employ both dampers or a plurality of dampers operatively connected and adapted 75 to operate substantially as herein described and claimed.

Although the damper 22 is by preference ordinarily operated or moved from its raised or open position to or toward its lowered 80 or closed position with and by means of the automatic operation of the air-actuated damper operating mechanism or weighted current-actuated damper 11 and lever arm and rod connections, as already described, it 85 is possible to permit the damper 22 to move to or toward its closed or lowered position simultaneously with or upon the closing of the combustion chamber door and without operating or lowering the weighted damper 11, by simply connecting the chain or flexible element 30 or 30' with an opening 55 nearer to the pivot or axis 34 of the bell crank lever 32 than the hole 56 in which said chain or flexible element is shown in 90 Fig. 2, so as to shorten the effectual length of the lever arm to which said chain or flexible element is adjustably connected. A series of openings 55, 56 is provided in the lever arm 32, for permitting the adjustment 95 of the chain or flexible element to different positions with respect to the axis or pivotal center of said bell crank.

By connecting the chain or flexible element with the lever 32 at the point indicated by the position of the hole 55 the damper 22 will be permitted to move downward toward or to its desired lowered, or partly opened or desired adjusted position with or upon the closing of the fire-box or combustion chamber door 4. And said damper 22 will nevertheless be opened sufficiently by the opening of the fire-box door to permit the smoke to pass into the flue, and to prevent the smoke from escaping through the 110 fire-box door when opened for the purpose of replenishing the fire, or for any purpose.

The automatic operation of the weighted current-actuated damper operating means or damper 11 will, however, in any case insure the proper lowering or operation of the damper 22 to or toward its closed position, as already described.

I claim:

1. In a mechanism of the class described, 125 the combination of a flue forming a fluid passage adapted to permit a current to pass therethrough from a combustion chamber, a damper rockingly mounted upon an axis and adapted to permit such current to pass 130

the damper in its open position at or below a predetermined speed without closing the damper, said damper being adapted to be automatically operated toward its closed position when the current passing the damper exceeds such predetermined speed, releasable damper-holding means operatively connected with and in movable relation to said damper, for releasably holding the same in its initial open position, and damper-operating means located outside of said passage and operatively connected with said releasable damper-holding means and adapted to move said damper to its initial open position.

2. In a mechanism of the class described, the combination of a flue forming a fluid passage adapted to permit a current to pass therethrough from a combustion chamber, a damper rockingly mounted upon an axis and adapted to permit such current to pass the damper in its open position at or below a predetermined normal speed, said damper adapted to be automatically operated toward its closed position when the current passing the damper exceeds such predetermined normal speed, damper-operating means operatively connected with said damper, for moving the same from its closed to its initial open position, and means for operatively connecting said damper-operating means with a furnace door.

3. In a mechanism of the class described, the combination of a flue forming a fluid passage adapted to permit a current to pass therethrough from a combustion chamber, a damper rockingly mounted upon an axis and adapted to permit such current to pass the damper in its open position at or below a predetermined normal speed of movement of such current, said damper having its axis and center of gravity so disposed with respect to each other as to permit the damper to be automatically operated toward its closed position and the center of gravity of the damper shifted from one side to the other of the axis of the damper when the current passing the damper exceeds such predetermined normal speed, and damper-operating means operatively connected with said damper and adapted to be operatively connected with a furnace door.

4. In a mechanism of the class described, the combination of a flue forming a fluid passage adapted to permit a current to pass therethrough from a combustion chamber, a damper rockingly mounted upon an axis and adapted to permit such current to flow freely past the damper at or below a predetermined normal speed of movement of such current without closing the damper, said damper being adapted to be automatically operated in one direction by the action of such current moving past the damper at a speed in excess of such predetermined nor-

mal speed, and automatic damper-operating means located outside of said passage operatively connected with the damper, for operating it automatically in an opposite direction to initial position.

5. In a mechanism of the class described, the combination of a flue forming a fluid passage adapted to permit a current to pass therethrough from a combustion chamber, a damper rockingly mounted upon an axis and extending transversely with respect to said passage and adapted to permit such current to flow freely past the damper at or below a predetermined normal speed of movement of such current without operating the damper, said damper being adapted to be automatically operated in one direction of its movement by the action of such current moving past the damper at a speed in excess of such predetermined normal speed, damper-operating means operatively connected with the damper, for operating it in an opposite direction, automatically releasable stopping means operatively connected with and adapted to limit the movement of the damper, and means for operatively connecting said damper-operating means with a furnace door.

6. In a mechanism of the class described, the combination of a flue forming a fluid passage adapted to permit a current to pass therethrough from a combustion chamber, a damper rockingly mounted upon an axis and extending transversely with respect to said passage and adapted to permit such current to flow freely past the damper at or below a predetermined normal speed of movement of such current without operating the damper, said damper being adapted to be automatically operated in one direction of its movement by the action of such current moving past the damper at a speed in excess of such predetermined normal speed, damper-operating means operatively connected with the damper for operating it in an opposite direction to initial position, and adjustable stopping mechanism adapted to operatively engage and limit the movement of the damper.

7. In a mechanism of the class described, the combination of a flue forming a fluid passage adapted to permit a current to pass therethrough from a combustion chamber of a furnace, a damper rockingly mounted and adapted to permit such current to flow in said passage at or below a predetermined normal speed of movement of such current without closing the damper, said damper being adapted to be automatically operated in one direction of its movement by the action of such current moving past and in contact with the damper at a speed in excess of such predetermined normal speed, a second damper, for controlling the effectual area of said passage, and damper-operating means

located outside of said passage operatively connected with and forming a connection between said dampers.

8. In a mechanism of the class described, 5 the combination of a flue forming a fluid passage adapted to permit a current to pass therethrough from a combustion chamber, a damper rockingly mounted in and adapted to permit such current to flow freely through 10 said passage at or below a predetermined normal speed of movement of such current without operating said damper, said damper being adapted to be operated in one direction of its movement by the action of such 15 current moving at a speed in excess of such predetermined normal speed, a second damper, for controlling the effectual area of said passage, and releasable damper-holding means operatively connected with said last- 20 mentioned damper and adapted to releasably hold the same in open position, said holding means being adapted to be automatically operated to releasing position by 25 said first-mentioned damper.
9. In a mechanism of the class described, 30 the combination of a flue forming a fluid passage adapted to permit a current of air and gases to pass therethrough from the combustion chamber of a furnace, a damper mounted in such passage and adapted to 35 permit such current to flow past the damper at or below a predetermined normal speed of movement of such current without operating said damper, said damper being 40 adapted to be automatically operated in one direction of its movement by the action of such current moving at a speed in excess of such predetermined normal speed, a second damper mounted in said passage, for controlling the effectual area of the passage, and damper-releasing and operating means 45 located outside of said passage and operatively connected with and adapted to release and permit the operation of the last- 50 mentioned damper and operatively connected with and adapted to be actuated by said first-mentioned damper.

10. In a mechanism of the class described, 55 the combination of a flue forming a fluid passage adapted to permit a current of air and gases to pass therethrough from the combustion chamber of a furnace, a damper mounted in such passage and adapted to permit such current to flow freely past such 60 damper at or below a predetermined normal speed of movement of such current without operating said damper, said damper being adapted to be automatically operated in one direction of its movement by the action of such current moving at a speed in excess of such predetermined normal speed, a second damper mounted in said passage, for controlling the effectual area of the passage, 65 damper-releasing and actuating means operatively connected with and forming a con-

nection between said dampers and means for operatively connecting said damper-releasing and actuating means with a furnace door.

11. In a mechanism of the class described, 70 the combination of a flue forming a fluid passage adapted to permit a current of air and gases to pass therethrough from a combustion chamber of a furnace, a damper rockingly mounted in such passage and adapted to permit such current to flow past such damper at or below a predetermined normal speed of movement of such current without operating said damper, said damper being adapted to be automatically operated 75 in one direction of its movement by the action of such current moving in excess of such predetermined normal speed, a second damper mounted in said passage, for controlling the effectual area of the same, damper-releasing mechanism connected with and forming a connection between said dampers and adapted to be actuated by the movement of the first-mentioned damper for releasing 80 and permitting the movement of the last-mentioned damper, and damper-operating means located outside of said passage and connected with said damper-releasing mechanism, for returning said dampers to initial 85 position.

12. In a mechanism of the class described, 90 the combination of a flue forming a fluid passage adapted to permit a current of air to pass therethrough from a combustion chamber of a furnace, a damper rockingly mounted in such passage and adapted to permit such current to flow past such damper at or below a predetermined speed of movement of such current without operating 95 said damper, said damper being adapted to be actuated by the action of such current moving at a speed in excess of such predetermined speed, a second damper mounted in said passage, for controlling the effectual area of the same, a damper-releasing and 100 damper-operating bar operatively connected with and forming a connection between said dampers and adapted to releasably hold said last-mentioned damper in open position 105 when the first-mentioned damper is in initial open position, and operating means operatively connected with said damper-operating bar and adapted to be operatively connected with and automatically operated by a furnace door.

13. In a mechanism of the class described, 110 the combination of a flue forming a passage adapted to permit a current of air and gases to pass therethrough from a combustion chamber of a furnace, a damper for controlling the effectual area of said passage, 115 damper-operating means extending into said passage and adapted to be automatically actuated in one direction by the action of such current, and damper-operating 120

means adapted to be connected with a door of such furnace and operatively connected with and forming a connection between said damper and said first-mentioned damper-operating means, for moving the same to initial position.

14. In a mechanism of the class described, the combination of a flue forming a passage adapted to permit a current of air and gases 10 to pass therethrough from a combustion chamber of a furnace, a damper for controlling the effectual area of said passage, damper-operating means rockingly mounted and adapted to be automatically actuated in 15 one direction by the action of such current

moving through said passage at or exceeding a predetermined speed of movement of such current, connecting rod and lever mechanism operatively connected with and forming an adjustable connection between said 20 damper and damper-operating means, and means for operating said connecting rod and lever mechanism to move said damper and said first-mentioned damper-operating 25 means to initial position.

Signed at Chicago, in the county of Cook and State of Illinois, this 14th day of October, 1924.

WILLIAM J. PFEIFER.
